UNITED STATES PATENT OFFICE.

RUDOLF HUNDHAUSEN, OF CHARLOTTENBURG, NEAR BERLIN, GERMANY;
ASSIGNOR TO ERNEST H. HUNDHAUSEN, OF NEW YORK, N. Y.

COUNTING DEVICE.

SPECIFICATION forming part of Letters Patent No. 423,690, dated March 18, 1890.

Application filed June 5, 1889. Serial No. 313,215. (No model.)

To all whom it may concern:

Be it known that I, RUDOLF HUNDHAUSEN, of Charlottenburg, near Berlin, Germany, a citizen of Germany, have invented certain new and useful Improvements in Counting Devices, of which the following is a specification.

This invention relates to improvements in that class of counting devices that are used for automatically counting numbers, revolutions, reciprocations, or other movements.

The object of my invention is to provide a counting device which is simple in construction, not apt to get out of order, closed tightly so that no dust or moisture can get into it, and in which the parts can easily be interchanged and one substituted for the other, thus preventing undue wear of certain parts.

The invention consists in the construction and combination of parts and details, as will be fully described hereinafter, and finally pointed out in the claims.

Figure 1 of the accompanying drawings represents a longitudinal section of this improved counting device, a portion of the counting-wheels being in edge elevation. Fig. 2 represents a side elevation of the counting device, showing the covered slot through which the proper figures on the counting-wheels may be read. Fig. 3 represents the left-hand end of the device, the head being shown as integral with the casing and the counting-wheel shaft as having a clamping-nut. Fig. 4 represents a transverse section of the counting device on line 4-4 of Fig. 1. Fig. 5 represents an elevation of one side of one of the counting-wheels and a portion of the mechanism for communicating motion from one wheel to another. Fig. 6 is a side elevation of the other side of one of the counting-wheels. Fig. 7 represents a transverse section of the counting-wheel shaft and a side elevation of one of the cams fixed thereon for actuating a counting-wheel. Fig. 8 represents a transverse section of this improved counting device on line 8-8 of Fig. 1. Figs. 9, 10, 11, and 12 represent transverse sections of the counting-wheel shaft, the fixed cam thereon, and side elevations of the same side of one of the counting-wheels, showing the different positions thereof in relation to

the actuating-cam. Fig. 13 is a side elevation of one of the counting-wheels, showing the track of the pawl thereon.

Similar letters of reference indicate corresponding parts.

The counting-wheels $Z' Z^2 Z^3 Z^4 Z^5 Z^6 Z^7$, on the rims of which the numerals 0, 1, 2, 3, 4, 5, 6, 7, 8, and 9 are produced in any suitable manner, are mounted close to each other on the central longitudinal shaft A of the cylindrical casing, the latter having a longitudinal slot B, through which one row of numerals of the number-wheels $Z' Z^2$, &c., show.

The casing is composed of a cylinder C and the two heads D' and D^2 , into which the ends of the shaft A are screwed. If desired, the head D' may be made integral with the cylinder C and the left-hand end of the shaft A provided with a threaded end, which projects through said closed end of the cylinder, and a nut M (see Fig. 3) is then screwed on said projecting end of the shaft. The shaft A thus also serves for holding the two heads or ends firmly on the cylinder. The said shaft A is provided with a longitudinal bore f, from which a series of channels f' extends radially to the surface of the shaft, forming oil-ducts by means of which the apparatus can be lubricated. A screw f'' is screwed into the end of the bore f after the oil has been supplied, for the purpose of excluding dust and dirt. The slot B is to be closed by a suitable pane of glass for the purpose of excluding dust, which glass plate, however, is so arranged that it can be removed to permit of adjusting the single-number wheels.

In order to prevent dust, &c., from passing into the mechanism, the units-wheel Z' is not driven by means of a pin or other device passing through a slot in the end of the casing, as has been customary heretofore, but is operated by an actuating-shaft H, that is passed through a collar or projection O on the outer surface of the head D^2 , and provided at its outer end with a crank W, to which the rod or mechanism is applied that is operated by the machine or other device, the strokes, rotations, or reciprocations of which are to be counted.

On the inner end of the shaft H is pivotally mounted the lever U, the said lever having

an elliptical slot or opening, the walls of which surround and are adapted to contact with the shaft A. On the swinging end of said lever a pawl k is mounted, which is provided at 5 one end with a recess or notch for receiving the pins projecting from the units-wheel Z', and at the other end it is provided with an arm k', which is pressed against the stop-pin u by a spring t, secured on said lever U. A 10 check-pawl h, also having one end recessed to receive the said pins on the units-wheel, is pivoted to the inner side of the head D² and is provided with an arm h', which is pressed against a stop-pin v by a spring h².

15 From one side of each number-wheel Z' Z², &c., ten pins s⁰ s' s² s³ s⁴, &c., project laterally and are equidistant from one another. On the opposite side of each wheel a lever K is pivoted at K', and is provided on its swinging 20 end with a laterally-projecting pawl E, made approximately triangular in shape and having its top slightly beveled. A spring F secured to the side of the wheel presses said lever K against a stop-pin J. Between each 25 two number-wheels a split collar L is clamped by a screw T, in a fixed position on the shaft A, and said collar is provided with a downwardly-projecting arm N, having a cam P', the bottom edge of which is curved concentric with the center of the shaft A, between the points P and Q, (see Figs. 5 and 7,) and from the point Q to the point R is curved upward.

As shown in Fig. 1, the rims of the wheels 30 Z' Z², &c., are formed with annular flanges projecting from both sides of the body, thus forming a recess between each two wheels, in which recesses are mounted the simple mechanisms for communicating motion from one 35 wheel to another. It is evident that the wheel counting units makes ten times as many rotations as the wheel counting tens, and the wheel counting tens ten times as many rotations as the wheel counting hundreds, and so 40 on. The wheel counting units will wear out about ten times as soon as the tens-wheel, and would have to be replaced first of all. As all the counting-wheels are alike in construction 45 and shape, one can be replaced by another, and after the apparatus has been used for a time the units-wheel, which has been used most, can be substituted for the last wheel, in this case the millions-wheel and all the other wheels moved to the right the distance 50 of one wheel, and so on. The wheels can thus be interchanged seven times, if seven wheels are used, as in the case shown, and thus the apparatus will last seven times as long as the ordinary counting apparatus.

55 60 The operation is as follows: the arm W is rocked to and fro and the pawl k of the lever U acts directly on the pins s⁰ s' s² s³, &c., of the units-wheel Z'. When the said arm W swings in the direction of the arrow x', Fig. 4, 65 the pawl k engages one of the pins on the units-wheel and turns said wheel in the direction of the arrow x² (see Fig. 4) until the left-

hand inner edge of the ring-shaped lever U strikes against the hub of the units-wheel, whereby the units-wheel has been rotated in 70 the direction of the arrow x² the distance of one tooth. When the arm W is swung back in the reverse direction of the arrow x', its pawl k is depressed by contact with the next pin s⁰ s', &c., to the left until it clears 75 the same, when by the action of the spring t it rises so as to engage the said pin. The pawl h prevents the units-wheel Z' from moving in the reverse direction of the arrow x². The pawls E on the number-wheels are 80 normally in the position shown in Figs. 6, 10, and 11—that is to say, they are pressed against their respective stop-pins J by the springs F. When a pawl E arrives at the bottom, it abuts against the upwardly-projecting end of the 85 cam P', and is thereby pressed down, as shown in Figs. 5 and 8, and engages one of the pins s⁰ to s⁹ of the adjacent counting-wheel, whereby said pin and its wheel are carried around the distance of one numeral. By the time that said 90 wheel has been rotated the distance of one numeral the pawl E, that has just been subjected to the action of the cam P', arrives at the end of said cam at P and is thrown toward the center—that is, against the stop-pin J by the 95 spring F—whereby said pawl is disengaged from one of said pins and the number-wheel, that has just been rotating the distance of one number, remains stationary. Only during the one-tenth of a rotation does the pawl 100 E of any one wheel remain engaged with a pin of an adjacent wheel. The units-wheel once in each rotation rotates the tens wheel Z² one-tenth—that is, a distance of one numeral, or, in other words, the units-wheel makes ten 105 rotations for every rotation of the tens-wheel, and so on.

Fig. 13 shows the track or course of the pawl E by the dotted lines m.

After the glass plate covering the slot B 110 has been removed from said slot any one of the number-wheels can be adjusted to show the zero or any desired number on the face without interfering with any of the other wheels.

Having thus described my invention, I 115 claim as new and desire to secure by Letters Patent—

1. In a counting device, the combination of a fixed shaft, a rotatable number-wheel thereon, provided with a flanged rim and having pins projecting from one of its sides within said flanged rim, an actuating-shaft parallel to said fixed shaft, a lever loosely mounted on said actuating-shaft and having an elliptical slot therein, and a spring-pressed pawl on the free end of said lever adapted to engage the pins of said number-wheel, the walls of the elliptical slot surrounding and being adapted to coact with said fixed shaft.

2. In a counting device, the combination of a fixed shaft, two or more number-wheels provided with flanged rims and mounted on said shaft, an actuating-shaft parallel to said fixed

shaft, a crank-arm on said actuating-shaft, a lever having an elliptical slot mounted on said actuating-shaft, a spring-pressed pawl on said lever, fixed arms on said fixed shaft 5 between said number-wheels, and cams on the ends of said arms, each of said number-wheels having on one of its sides and within the flanged rim thereof projecting pins, and on the other side a pivoted lever with a

spring-pressed pawl adapted to engage the 10 pins of the adjacent wheel.

In testimony that I claim the foregoing as my invention I have signed my name in presence of two subscribing witnesses.

RUDOLF HUNDHAUSEN.
